DESIGN.

—o—
J. REICHENSTEIN.
HEATING STOVE.

No. 17,830.

Patented Oct. 25, 1887.

UNITED STATES PATENT OFFICE.

JOHN REIFENSTEIN, OF SYRACUSE, NEW YORK, ASSIGNOR TO THE SYRACUSE STOVE COMPANY, OF SAME PLACE.

DESIGN FOR A HEATING-STOVE.

SPECIFICATION forming part of Design No. 17,830, dated October 25, 1887.

Application filed August 1, 1887. Serial No. 245,896. Term of patent 7 years.

To all whom it may concern:

Be it known that I, JOHN REIFENSTEIN, of Syracuse, in the county of Onondaga, in the State of New York, have invented new and useful Improvements in Designs for Stoves, of which the following, taken in connection with the accompanying photographs, is a full, clear, and exact description.

This design is intended for the ornamentation of stoves, more particularly parlor stoves; and it consists in the novel and tasty contour of certain parts and the embellishment of the surfaces of the various parts of the stove, namely:

15 First. The so-called "skirt" A, which I embellish by a series of rosettes, *a a*, arranged in sets, with intervening bars, *a' a'*, and in a row extending lengthwise the skirt. Below said row of rosettes and bars are arranged horizontal bars *b b*, terminating in loops *b' b'* near the center of the skirt, and in said loops are arranged the rosettes *c c*, and on the bars *b b* and loops *b' b'* are respectively the pendants *d d'*, trimmed with drops *e e*.

25 Second. The base B, which I ornament by rosettes *f f* and intervening bars, *f' f'*, arranged in a row extending lengthwise the base, and with beads *f'' f''* above and below the said bars, all arranged in the panel *g*.

30 Third. The door C, which is of the form of a hood or swell, C', having bars *h h* extending lengthwise the same, and a panel, *i*, at the center, and beaded faces *k k* at opposite sides of said panel.

35 Fourth. The bracket D, the side rails, *l l*, of which are S-shaped, and under the said rails are reticulated vertical panels *l' l'*. The back *m* is embellished by a field of small panels, and the shelf *m'* is beaded and curved downward at the front to conform to the curvature of the lower portion of the side rails, *l l*.

Fifth. The corners of the stove, which I ornament by twisted columns *n n*, having caps of the form of animal-heads, *n'*.

45 Sixth. The doors E E, which I embellish by a central rosette, *o*, translucent plates *o' o'* at opposite sides of said rosettes, bars *p p* above and below said rosette and plates, and branches *q q' q'*, extending, respectively, from the cen-

ters of the bars and from the sides of the plates *o' o'*.

Seventh. The doors F F, which I embellish by a central rosette, *r*, translucent plates *r' r' r''*, respectively at opposite sides of and directly over the rosette, the bar *s*, extending across the bottom of the rosette and plates *r' r'*, the bars *s'*, extending across the top of the plates *r' r'* and up at the opposite sides of the plate *r''*, the branches *t t t*, extending from the plates and all arranged in a panel, and with a row of small panels, *u u*, under the aforesaid panel.

Eighth. The top portion, U, of the stove, which I embellish by an arch, U', divided at the center and terminating in scrolls *u' u'* 65 thereof, the panel *x* under said arch, and the rosettes *y y* and leaves *z z* in said panel.

Ninth. The dome of the stove, which I embellish by an annular band, I, brackets *N N*, extending radially from said band, panels *O* 7c *O* between the brackets, tiles *v v* in the centers of said panels, rosettes *v' v'* at opposite sides of the tiles, and the dome *T*, having the scalloped projecting edge *w*.

Tenth. The legs L, ornamented by the semi-elliptical garland *o'* around its top portion, and radial ribs extending from the center of the top to the said garland. 75

What I claim is—

1. The design for a stove, consisting of the imitation, *o'*, of a shell on the legs L, the horizontally-elongated pendants *d d'* on the skirt A, the panel *g*, with rosettes *f f* in said panel on the base B, the hood C' on the door C, with the panel *i* on said hood, the brackets D, having the reticulated vertical panels *l' l'* and the downward-curved shelf *m'*, the twisted columns *n n* on the corners of the stove, rosettes *o* and *r*, respectively on the doors E and F, the centrally-divided arch U' across the top 90 portion of the stove, the annular band I above said arch, and the dome T above said band, substantially as described and shown.

2. In a design for a stove, the ornamentation of the skirt A, consisting of the horizontal bars *b b*, terminating in loops *b' b'* near the center of the skirt, rosettes *a a* above said bars, rosettes *c c* in the loops, and horizontally-elong-

- gated pendants $d d' d''$, trimmed with drops $e e$, as shown.
3. In a design for a stove herein shown and described, the ornamentation of the base B, consisting of the panel g , rosettes $f f'$, and intervening bars, $f' f''$, arranged in a row extending lengthwise the panel, and beads $f'' f'''$ above and below the said bars, substantially as shown.
- 10 4. In a design for a stove herein shown and described, the door C, the swell C' on the door C, bars $h h$, extending lengthwise said swell, the panel i at the center of the swell, and beaded faces $k k$ at opposite sides of said panel, as set forth and shown.
- 15 5. In a design for a stove herein shown and described, the ornamentation of the bracket D, consisting of the vertical S-shaped side rails, $l l$, the reticulated vertical panels $l' l'$ under said rails, the paneled back m , and the beaded shelf m' , curved downward at the front to conform to the curvature of the lower portion of the side rails, $l l$, substantially as described and shown.
- 20 25 6. In a design for a stove herein shown and described, the twisted columns $n n$ at the corners of the stove, and caps on said columns of the form of animal-heads, as shown.
7. In a design for a stove herein shown and described, the ornamentation of the doors E E, consisting of the central rosette, o , translucent plates $o' o'$ at opposite sides of said rosettes, bars $p p$ above and below said rosette and plates, and branches $q q$ and $q' q'$, extending, respectively, from the centers of the bars and from the sides of the plates $o' o'$, substantially as shown.
- 30 35 8. In a design for a stove herein shown and described, the ornamentation of the doors F F, consisting of the central rosette, r , translucent plates $r' r' r''$, respectively at opposite sides of and directly over the rosette, the bar s , extending across the bottom of the rosette and plates $r' r'$, the bar s' , extending across the top of the plates $r' r'$ and up at opposite sides of the plate r'' , the branches $t t t$, extending from the plates, all arranged in a panel, and the rows of panels $u u$ under the aforesaid panel, as shown.
9. In a design for a stove herein shown and described, the top ornamented by the arch U', stove divided at the center and terminating in scrolls $u' u'$ thereat, the panel x in said arch, and the rosettes $y y$ and leaves $z z$ in said panel.
10. In a design for a stove herein shown and described, the annular band I, brackets N N, extending radially from said band, panels O O between the brackets, tiles $v v$ in the center of said panels, rosettes $v' v'$ at opposite sides of the tiles, and the dome T, having the scalloped projecting edge w , substantially as described and shown.
11. In a design for a stove herein shown and described, the legs L, ornamented by the semi-elliptical garland o' around its top portion, and radial ribs extending from the center of the top to the said garland, as shown.
- In testimony whereof I have hereunto signed my name and affixed my seal, in the presence of two attesting witnesses, at Syracuse, in the county of Onondaga, in the State of New York, this 5th day of May, 1887.
- JOHN REIFENSTEIN. [L. S.]
